UNITED STATES PATENT OFFICE.

GEORG LUDWIG GANSS, OF GROSS-UMSTADT, GERMANY.

HYDRAULIC STARTER FOR ELECTROMOTORS AND THE LIKE.

Application filed May 28, 1923. Serial No. 642,126.

To all whom it may concern:

Be it known that I, GEORG LUDWIG GANSS, a citizen of the German Empire, and resident of Gross-Umstadt, Germany, have invented certain new and useful Improvements in Hydraulic Starters for Electromotors and the like; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to a hydraulic starter for electro-motors and the like the gasometer type in which the throwing in and out of the resistance is controlled by the raising and lowering of a bell dipping into a receptacle for liquid. The receptacle or the bell serves directly as electrode. The novelty of the starter consists in that on the bell, a second electrode is arranged which with continuous current or alternating current works alone with the bell, or with three-phase current, also with a receptacle for liquid. In order to prevent a contact between the bell or electrode and the receptacle for a liquid ribs of insulating material are arranged on the bell or on the inner surface of the receptacle. Arrangements may also be made to partly cover both elements with wood or with other insulating material in order to vary accordingly the size of the electrode surface. A further improvement relates specially to the construction of a locking mechanism designed to maintain the bell in its upper extreme position. The short-circuiting device has been improved at the same time. The invention consists in that on the rim of the receptacle, a spring-controlled rotatable ring is arranged which has three supporting flaps on which the guiding and insulating ribs of the bell bear when said bell is in the highest position. When the ring is being rotated, the supporting flaps slip from under the ribs of the bell to release the bell and allow it to sink, the supporting flaps being pressed at the same time by the action of the springs of the ring laterally against the insulating ribs of the bell for braking said bell. Elastic contacts are further arranged on the bell which at the lowest position of

the bell come in contact with corresponding metal contacts of the ring.

A further improvement of the hydraulic starter consists in that care has been taken to gradually increase the speed of the descending movement of the bell so that the spilling of the liquid by a sudden shock is avoided. With this object in view the supports for holding the bell in the highest position are inclined so that the bell may gradually slide down the same. The releasing of the short-circuiting device and the supply of current to the several poles of the starter are further improved.

Several embodiments of the invention are shown, by way of example, on the accompanying drawings, wherein:

Fig. 1 shows in longitudinal section, and

Fig. 2 in plan view the preferred form of construction.

Figs. 3 and 4 show in side elevation and plan view a modified form of construction.

A third form of construction of the hydraulic starter is shown in Fig. 5 in longitudinal view and in Fig. 6 in plan view partly in section, the bell being at the highest position.

Fig. 7 is a view similar to Fig. 6 the parts being shown in their position after a part rotation of the ring.

Figs. 8, 9 and 10 show a constructional detail on enlarged scale.

Fig. 11 shows a special device for releasing the locking mechanism for the bell.

Fig. 12 shows in longitudinal section, and

Fig. 13 in a plan view a further modified form of construction.

Fig. 14 illustrates on a larger scale a constructional detail.

Figs. 15 and 16 show in side elevation, partly in section, and in plan view respectively, another form of construction.

Figs. 17, 18 and 19 show each another form of construction.

According to Figs. 1 and 2 the bell 1 has an outer electrode 2 and it is guided by means of a tube 3 on a vertical rod at the upper end of which a handle 4 is arranged. The locking mechanism is designated by 5. In the liquid receptacle 6 corner ledges 7 of insulating material are arranged the lower ends 8 of which are bent at right angles inwardly to prevent the contact between the electrode 2 and the bottom of the receptacle. On the corners of the electrode 2 welts 9

are formed with the aid of beads into which boards of wood or of any other insulating material may be inserted in order to reduce the surface of the electrode. The total resistance varies according to whether more or less of such wooden boards are inserted. If the receptacle is used as electrode the inner wall of this receptacle may be partly covered by such wooden boards. The liquid receptacle 6 is preferably insulated on the outside, for instance by a coating of enamel or by a wooden envelope. For three-phase current the liquid receptacle is preferably connected to earth.

15 The operation of the hydraulic starter is as follows:—The starting is effected in such a manner that the bell 2, secured in its highest position by the locking mechanism 5, is released together with its electrode 2 so that it sinks gradually into the liquid, the air flowing out through the outlet orifice 10. The resistance is thus gradually reduced and a gradual starting is produced. At the lowest position of the bell the contacts 11 are closed again whereby the starter is short-circuited. An air inlet 12 serves for the inflow of air at the raising of the bell.

In order to reduce the cost of manufacture the electrodes may be mounted on the outer surface of the bell and they may have the shape as shown in Figs. 3 and 4 in side elevation and plan view. The electrode 2 has at the upper end two flaps 13 which grip around the bell, insulating means being inserted between the electrode and the bell. These electrodes are easy to be exchanged against fresh electrodes in case they should be worn.

Under certain conditions electrodes of this kind may be arranged in the liquid receptacle instead of using the liquid receptacle itself as electrode in order to avoid the destruction of the receptacle.

As shown in Figs. 5 to 11 the hydraulic starter consists again of a receptacle 14 in which the bell 15 is movably mounted. This bell carries the ledges 16 of insulating material designed to prevent the bell from coming in contact with the inner surface of the receptacle. These ledges are interrupted at 17 in proximity of the lower end and one of said ledges has at its upper end a curved extension 18.

On the rim 19 of the receptacle 14 a ring 20 of insulating material is mounted which has a handle 21. The ring is guided by means of two studs 22 projecting from the receptacle and engaging with slots 23 of the ring, the springs 24, designed to maintain the ring in such a position that the studs 22 stand always approximately at the centre of the slots 23, being arranged at either side of said studs 22.

The ring 20 has three supporting flaps 25 projecting over the inner circumference of

the ring and adapted to engage with the interruptions 17 of the supporting ledges 16 as shown in Fig. 6. On the receptacle insulating pieces 26 are arranged which serve as stops and prevent the bell from rotating 70 with the ring.

When the bell is in its highest position the supporting flaps 25 engage with the interruptions 17 of the insulating ledges 16 so that the bell is maintained in this position 75 by said supporting flaps. When the starter has to be thrown in, the handle 21 of the ring 20 is pulled to one side so that the supporting flaps 25 get out of the interruptions 17 of the insulating ledges 16. The bell is 80 thus liberated and sinks in the receptacle, the resistance decreasing continuously as the surface in contact with the liquid increases gradually. After the handle 21 has been released the flaps 25 are pressed by the action 85 of the springs 24 against the sides of the supporting ledges 16, whereby the descending bell is braked so that the liquid is prevented from flowing over suddenly. The stops 26 prevent the bell from rotating. If 90 the bell has arrived approximately at its lowest position the one of the flaps 25 moves along the curve 18 of the corresponding insulating ledge 16 whereby the springs of the ring are put under increased tension. The flaps 25 jump therefore, as soon as the bell is at its extreme lower position, over the upper edge 27 of this ledge 16 so that the ring returns to its initial position. The sudden movement which is thus produced 95 serves for operating the short-circuiting device.

This short-circuiting device consists of two carbon brushes 28 adjustably mounted on the bell and controlled by springs 29. The special arrangement of these brushes is shown in Figs. 8, 9 and 10. The holders 30 for the brushes 28 are box-shaped and the bottom plate 31 of the box is inserted into a welt on the bell to produce a metallic contact so that the brush support is in electric connection with the bell. The welt may be also connected with the electrode. A clamping screw 33 serves for holding the brush support securely in the welt. By displacing 110 the brush support in the welt the brush if worn can be brought nearer to the ring 20. The brush support presents at each side an angular slit 34 in which the brushes 28 are guided by means of studs 35. The spring 36 serves for pushing the brush 28 forward.

Two metal plates 37 are arranged on ring 20 which are bent downward and bear on the rim of the receptacle to produce a current conducting connection. The brushes 28 come in contact with these plates 37 when the bell has arrived at its lowest position whereby the short-circuiting is produced.

A handle 38 serves for pulling the bell up. Fig. 7 shows that the two plates 37 are 130

slightly bent so that the brushes 28 engage first with these bent parts. Only when the one flap 25 slips off the edge 27 of the insulating ledge 16 the ring 20 is rapidly rotated through the action of the springs 24 whereby the brushes 28 are brought in contact with the metal plates 37.

If the starter is used for three-phase current the interruptions 17 are arranged so that a complete throwing out of gear of the starter is impossible, said interruptions 17 being arranged farther down for continuous current in order to permit of a complete throwing out of gear. The supporting flaps 25 may have rollers in order to reduce the friction and the wear on the insulating ledges 16.

The release of the locking mechanism by rotation of ring 20 may be effected also by a special device designed to prevent that at the further rotation of the ring the bell sinks rapidly and the liquid flows over the rim of the receptacle. This special device serves at the same time to prevent the ring 23 from being erroneously turned to the wrong side, whereby the carbon brushes would be stopped on the ring so that they cannot produce the short circuiting or so that they would even break off. This special device is shown in Fig. 11 and it consists of a rod 39 with press-button adjustably mounted in a casing 40 fixed on the receptacle, said rod having at its lower end a roller 41. A spring 42 serves for pulling the rod back into the position shown in Fig. 11.

If the rod 39 is being depressed the roller 41 is brought in contact with a curve 43 of the ring 20 which is of oblique direction so that the ring is laterally displaced for a determined distance corresponding with the curve. In this manner it is absolutely impossible to rotate the ring in the other direction. If the rod 39 is released again it returns to its initial position under the action of the spring 42. This device may act also from below on the ring 20. In this form of construction a protecting box may be arranged on the bell so that it extends over the receptacle and moves up and down with the bell, said protecting box liberating the switching in device when the bell is in the highest position.

In the form of construction shown in Figs. 12-14 the receptacle for the liquid is designated by 44. It has an outwardly bent flange 45 at the upper end on which the ring 46 is rotatably mounted, pins 47 at the upper ring 46 (Fig. 14) engaging with corresponding slits 48 of flange 45 to guide the ring 46. On the ring 46 blocks 50 are fixed by means of hinges 49, said blocks carrying on their inner surfaces the bows 51. These bows are inclined and serve as supports for the insulating ledges 52 of bell 53 located in the receptacle 44. If the bell 53 is in

its highest position the insulating ledges 52 are supported by said bows 51 so that the bell 53 is prevented from descending. The bell 53 carries the electrodes 54 which are insulated from the bell by means of rings 70 55 and 56. When the bell is at its highest position so that the greatest resistance is interposed the insulating ledges 52 rest upon the bows 51 and securely hold the bell in its position. As soon as ring 46 is rotated the 75 insulating ledges 52 slide down on the inclined bows 51 so that the bell sinks gradually into the liquid. The bell descends gradually until it has reached its lowest position. In this lowest position of the bell 80 the short-circuiting device is released in the following manner:

The ring 46 has two contact plates 57 and 58, contact pieces 59 and 60 being arranged on the bell. When the ring 46 is being rotated in order to release the insulating ledges 52 of the bell 53 a projection 61 of the ring is caught under a spring 62 fixed on the rim of the receptacle. The ring is thus securely held in its rotated position, the pull spring 63 arranged between stud 47 of the ring 46 and stud 64 of the flange 45 being put under tension. The contacts 59 and 60 stand laterally of the contact plates 57 and 58. When the bell arrives at its lowest position a nose 65 of said bell strikes against the end of spring 62 whereupon nose 61 of ring 46 is released. The ring is now free to rotate backward in the direction of the arrow (Fig. 14) under the pull of the spring 63 whereby the contacts 59 and 60 are brought in contact with the contact plates 57 and 58. The short-circuiting of the starter is thus produced.

If the bell 53 is pulled up again by means of the handle 56 the blocks 50 oscillate around their hinges 51 so that the insulating ledges 52 can freely move along until their ends come in contact with the bows 51. The blocks 50 drop back to their initial position so that the ledges 52 are again supported by the bows 51 and hold the bell 53 in its position. Flexible cables or the like may be used for supplying the current. The arrangement could however be made in such a manner as shown in Figs 15 and 16. According to these figures the upper flange 45 of the receptacle 44 is removable and held by a bayonet joint 67. It may however be fixed in any other convenient manner, for instance by screws or the like. At the lower end of receptacle 44 a similar flange 68 is arranged by means of which the hydraulic starter may be screwed on a table or the like. This form of construction of the removable flanges presents the advantage that the receptacle itself may be made of sheet iron and removable, the thicker, specially arranged flanges being made from cast iron or the like. For continuous current the lower 130

flange of the receptacle is mounted on insulating rollers. With regard to supply the current insulating pieces 69 and 70 are arranged on the upper flange 45 and on the 5 lower flange 68 respectively, a metal tube 71 being inserted between said insulating pieces. The metal tube has at its lower end a clamping piece 72 with a clamping screw 73 for the connection of the cable. On the upper 10 end of tube 71 a metal cast piece 74 is arranged the end of which engages with the insulating piece 69. A carbon brush 75 in the cast piece 74 is constantly pressed by a spring 76 against the metal rod 77 telescoped into tube 71 so that it can slide in said tube. This metal rod 77 is in metallic 15 connection with the plates 78 of the bell if the current is continuous current.

If three-phase current is used the plates 20 78 are fixed on an insulating ring 79 on the top of the bell and they are connected by leads 80 or 81 with the electrode and bell respectively (Fig. 16). At the upward and downward movement of bell 53 a metallic 25 current conducting connection with the supply cables attached at 73 is established by the plates 78, the rod 77 and the tube 71, the brush 75 maintaining constantly the contact between the rod 77 and tube 70 or cast 30 piece 74.

In this form of construction the short-circuiting brushes could also be carbon brushes 82 as shown in dotted lines in Fig. 16, said brushes being mounted under the 35 metal plates 78 in a convenient bearing and being controlled by the pressure of springs 83. The carbon brushes bear against the plates 84 of the ring 46 rotatably mounted on the rim of the receptacle.

40 Under certain conditions the brushes may be arranged so that they act in downward direction in which case the contact plates 84 are mounted upon the ring 46 instead of at the side of the same.

45 In the form of construction shown in Fig. 17 the liquid receptacle 44 is of such a height that it encloses the bell 53 and the electrodes 54 on this bell even if this bell is in the highest position. The ring 46 for 50 the switching in and for the short-circuiting is arranged approximately at the middle of the receptacle 44 and mounted in such a manner that it cannot move in upward direction. The ring carries the same short-circuiting device as described above and it

55 has a handle 85. The receptacle is closed by a lid 86 which covers also the bell 53 in its highest position. The handle 66 of the bell projects through the lid and has at its lower end the air inlet valve 87 for the bell. An air-outlet valve 88 arranged on the bell has a separate spindle so that air may 60 permanently flow out of the bell. The sinking velocity of the bell corresponds to the starting

65 of the motor with full load to be started

by means of the hydraulic resistance. If the motor has to be started with half load or with idle run the valve 88 is completely opened.

Guide rails 89, fixed on the inner wall of 70 the receptacle and insulated from said receptacle serve for supplying current to the electrodes, the brushes 90 of the bell moving along said rails. The guide rails 89 are connected with the current conducting wires by 75 terminals 91.

80 In order to permit to observe the liquid level in the receptacle a float 92 is arranged the rod of which projects through a funnel-shaped orifice 93 used for re-filling the receptacle, said rod terminating by a knob or by a hand 94 which indicates the position of the float. The operation of this form of construction is the same as that of the form of construction described at the beginning of 85 the specification.

85 The form of construction shown in Figs. 18 and 19 show hydraulic starters for three-phase current. With starters of this type the three electrodes must preferably be 90 tuned accurately for the three-phases, which can be done by covering the surfaces of the outer electrodes which are too great compared with the smaller surface of the bell. It is however more advisable to make the arrangement as shown in Fig. 18. The cylindrical electrode mounted on the bell 95 is subdivided into three part-electrodes 97 separated from one another by insulating bars 96, said part-electrodes corresponding to the 100 three phases. The starter is otherwise constructed as described with the exception that three sliding contacts for the transfer of current and accordingly three short-circuiting contacts must be provided.

105 Fig. 19 illustrates also a three-phase current starter but the three parts of the electrode are not mounted on the bell 95 but on the inner wall 98 of the receptacle. The three electrodes are designated by 99; they are insulated from one another and from the wall 98 of the receptacle. This form of construction comprises neither sliding contacts nor movable leads. The resistance is varied as the water column in the receptacle rises in consequence of the sinking of the bell and the distance of the electrodes is altered also through the intermediary of the sinking bell made of metal. The receptacle is lined internally with wood or any other convenient insulating material. It is filled with so much liquid that the motor begins to start if the 110 starter is at the released position, the further starting being controlled by the dipping in of the bell. In this form of construction the liquid receptacle is preferably of greater diameter and of lesser height in order to make the distance between the electrodes in the switched out state as great as 115 possible. The terminals for the leads are

120 125 130

designated by 100, the short-circuiting brushes by 101 and the blade springs fixed on the bell 95 by 102, the short-circuiting contacts of the ring being pressed on said 5 blade springs when the bell is at its lowest position.

If the brushes are horizontal the blade springs on the bell are slightly upwardly inclined so that when the bell descends they 10 press against the brushes from the side.

I claim:—

1. A hydraulic starter comprising in combination a liquid receptacle serving as electrode, a bell serving as electrode and a second electrode on said bell which works together with the bell for continuous or alternating current and for three-phase current together with the bell and liquid receptacle.

2. A hydraulic starter comprising in combination a liquid receptacle serving as electrode, a bell serving as electrode and a second electrode on said bell, projecting ribs of insulating material on said bell designed to prevent the contact between the electrode 25 and the liquid receptacle.

3. A hydraulic starter comprising in combination a liquid receptacle serving as electrode, a bell serving as electrode and a second electrode on said bell, projecting ribs of 30 insulating material on the inner wall of the liquid receptacle and on the bottom of the same for preventing the contact between the electrode and the liquid receptacle.

4. A hydraulic starter comprising in combination a liquid receptacle serving as electrode, a bell serving as electrode and a second electrode on said bell, and plates of insulating material, partly covering the surface of one of said electrodes.

40 5. A hydraulic starter comprising in combination a liquid receptacle serving as electrode, a bell serving as electrode and a second electrode on said bell, ledges on said bell forming welts, and boards of insulating material, inserted into said welts for partly covering the surface of the electrode.

6. A hydraulic starter comprising in combination a liquid receptacle serving as electrode, a bell serving as electrode and a second electrode on said bell, ledges on the inner wall of said liquid receptacle forming welts and boards of insulating material, inserted into said welts for partly covering the inner surface of said liquid receptacle.

55 7. A hydraulic starter comprising in combination a liquid receptacle serving as electrode, a bell in said receptacle, two electrodes on said bell and two lugs for removably fixing said electrodes on said bell.

60 8. A hydraulic starter comprising in combination a liquid receptacle, a bell in said liquid receptacle and several exchangeable electrodes.

65 9. A hydraulic starter comprising in combination a liquid receptacle serving as elec-

trode, a bell in said receptacle serving as electrode, a rotatable ring of insulating material on the rim of said receptacle, arms projecting from said ring, and insulating ribs on said bell having indentations 70 designed to engage with said arms when said bell is in the highest position.

10. A hydraulic starter comprising in combination a liquid receptacle serving as electrode, a bell in said receptacle serving as

75 electrode, a rotatable ring of insulating material on the rim of said receptacle having slits, arms projecting from said ring, and insulating ribs on said bell having indentations 80 designed to engage with said arms when said bell is in the highest position, studs projecting from said receptacle engaging with said slits of the rotatable ring, springs attached to said ring and to said 85 studs for maintaining said ring in a determined position and for returning the same to this position when it has been rotated by hand to release said insulating rib.

11. A hydraulic starter comprising in combination a liquid receptacle serving as electrode, a bell in said receptacle serving as

90 electrode, a rotatable ring of insulating material on the rim of said receptacle having slits, arms projecting from said ring, and insulating ribs on said bell having indentations 95 designed to engage with said arms when said bell is in the highest position, studs projecting from said receptacle engaging with said slits of the rotatable ring,

100 springs attached to said ring and to said studs for maintaining said ring in a determined position and for returning the same to this position when it has been rotated by hand to release said insulating ribs so that

105 said arms of the ring bear against the sides of said insulating ribs and brake the descending bell when said bell has been released.

12. A hydraulic starter comprising in combination a liquid receptacle serving as electrode, a bell in said receptacle serving as

110 electrode, a rotatable ring of insulating material on the rim of said receptacle having slits, arms projecting from said ring, and insulating ribs on said bell having indentations 115 designed to engage with said arms when said bell is in the highest position, studs projecting from said receptacle engaging with said slits of the rotatable

ring, springs attached to said ring and to said studs for maintaining said ring in a determined position and for returning the same to this position when it has been rotated by hand to release said insulating ribs,

120 a short-circuiting device on said ring, and a curved guide piece at the upper end of one of said insulating ribs designed to displace said ring at the end of the descending movement of the bell and putting said

125 springs under tension and to suddenly re-

- lease said ring so that said short-circuiting device is operated.
13. In a hydraulic starter of the type described having receptacle and bell electrodes the short-circuiting device consisting of a ring contact brushes fixed on the electrodes, and contact plates mounted on said ring in contact with the receptacle electrode and arranged to come into contact with said contact brushes.
14. A hydraulic starter of the type described adjustable brush holders on the electrode, contact brushes in said holders and springs in said holders for pressing said brushes against the contact plates.
15. A hydraulic starter of the type described comprising in combination a liquid receptacle, a bell in said receptacle, insulating ribs on said bell having indentations which are situated higher or lower in accordance with the kind of current used, a ring of insulating material on the rim of said receptacle, arms inwardly projecting from said ring designed to engage with said indentations of the insulating ribs.
16. In a hydraulic starter of the type described a bell, a receptacle, a receptacle for the bell and a ring on the receptacle, locking mechanism for the bell, an incline on said ring designed to release the locking mechanism of the bell and a press rod guided on said receptacle acting upon said incline.
17. A hydraulic starter comprising in combination a liquid receptacle serving as electrode, a bell in said liquid receptacle, an electrode on said bell, insulating ribs on said bell, a ring of insulating material on the rim of said receptacle, blocks of insulating material mounted on said ring and inclined bows inwardly projecting from said blocks serving as supports for said insulating ribs of the bell.
18. A hydraulic starter comprising in combination a liquid receptacle serving as electrode, a bell in said liquid receptacle, an electrode on said bell, insulating ribs on said bell, a ring of insulating material on the rim of said receptacle, blocks of insulating material mounted on said ring and inclined bows inwardly projecting from said blocks serving as supports for said insulating ribs of the bell, and hinges for attaching said blocks to said ring so that said blocks can give way when the bell is being pulled up.
19. A hydraulic starter comprising in combination a liquid receptacle serving as electrode, a bell in said liquid receptacle, an electrode on said bell, a rotatable ring of insulating material on the rim of said receptacle, a catch spring fixed to the upper end of said receptacle, a nose of said rotatable ring designed to engage with said catch spring, insulating ribs on said bell, means on said ring for supporting said insulating ribs when the bell is at the highest position, short-circuiting contacts, and an abutment on said bell designed to act upon said spring when the bell is at the lowest position so that said ring is released and rotated in operating the short-circuiting contacts.
20. A hydraulic starter of the type described comprising in combination with the bell, sleeves connected with the main line and rods projecting from the bell movably guided in said sleeves and serving as current conductors.
21. A hydraulic starter of the type described in which between the upper and the lower end of the receptacle insulating pieces are arranged, tubes mounted between said insulating pieces, rods attached to the bell serving as current conductors engaging with said tubes, elastic brushes on said tubes for producing the electric connection between said tubes and said rods.
22. In a hydraulic starter of the type described a receptacle and a bell therein insulating pieces between the upper and lower end of the receptacle, tubes inserted between said insulating pieces, plates on the bell, rods mounted on said plates and guided in said tubes, and short-circuiting brushes elastically mounted on said plates and designed to produce the electric connection between said rods and said tubes.
23. A hydraulic starter of the type described having a liquid receptacle and a bell therein, the liquid receptacle being of such a height that it projects over the bell even if said bell is at the highest position and a lid for closing said receptacle.
24. A hydraulic starter of the type described having a liquid receptacle and a bell, a rotatable bell locking ring arranged approximately at the middle of the liquid receptacle and a handle of said ring projecting in outward direction so that said ring may be operated from the outside.
25. A hydraulic starter of the type described having a liquid receptacle, a bell therein, insulated rails arranged on the inner wall of the liquid receptacle, brushes for the bell sliding on said rails and conducting the current to the bell.
26. A hydraulic starter of the type described having a liquid receptacle, and a bell having air outlet valve with a constantly uncovered hole of such a size that the outflow of air corresponds with the speed of the switching in under full load, the valve having to be opened under half load or idle run in order to accelerate the sinking of the bell.
27. A hydraulic starter of the type described, having a float mechanism for indicating the actual liquid level in the receptacle.

28. A form of construction of the hydraulic starter of the type described for three phase current in which the cylindrical electrode is subdivided into three parts insulated from one another and corresponding with the three phases.

29. A form of construction of the hydraulic starter of the type described having a bell and three electrodes mounted on the bell and insulated from the same.

30. A form of construction of the hydrau-

lic starter of the type described a bell and a receptacle therefor, the three electrodes mounted on the inner wall of the receptacle and insulated from the same.

15

In testimony that I claim the foregoing as my invention, I have signed my name.

GEORG LUDWIG GANSS.
